CLAIM

The ornamental design for a tablet computer, as shown and described.

DESCRIPTION

FIG. 1 is a front right upper perspective view of a tablet computer showing our new design.

FIG. 2 is a rear left lower perspective view of the tablet computer of FIG. 1.

FIG. 3 is another rear left lower perspective view of the tablet computer of FIG. 1.

FIG. 4 is a rear right upper perspective view of the tablet computer of FIG. 1.

FIG. 5 is a front view of the tablet computer of FIG. 1.

FIG. 6 is a rear view of the tablet computer of FIG. 1.

FIG. 7 is a right side view of the tablet computer of FIG. 1.

FIG. 8 is a left side view of the tablet computer of FIG. 1.

FIG. 9 is a top view of the tablet computer of FIG. 1; and, FIG. 10 is a bottom view of the tablet computer of FIG. 1. The broken lines in the drawings illustrate portions of the tablet computer and form no part of the claimed design.

1 Claim, 10 Drawing Sheets
